REFRIGERATION APPARATUS

Gerald P. Marcy, Springfield, Mass., assignor to
Westinghouse Electric & Manufacturing Com-
pany, East Pittsburgh, Pa., a corporation of
Pennsylvania

Application March 8, 1939, Serial No. 260,500

2 Claims. (Cl. 200—138)

My invention relates to control apparatus and it has for an object to provide improved apparatus of this kind.

A further object of my invention is to provide improved control apparatus for refrigerating machines which is inexpensive to construct and which may be readily applied to various forms of refrigerators.

It is a further object of the invention to provide an improved control apparatus employing a snap-acting thermal device that may be adjusted to maintain different temperatures.

A still further object of the invention is to provide an improved control mechanism including a hermetically sealed switch structure and to provide for adjustment of the switch structure so that the temperatures at which the contacts are opened and closed may be varied at will.

It is another object of my invention to improve the heat transfer qualities of a hermetically sealed control mechanism of the bi-metal thermostat type; and furthermore, by increasing the heat transfer to such a bi-metal thermostat to permit the use of larger temperature differentials for the bi-metallic thermostat element.

It is also an object of the invention to provide an improved control apparatus employing a bi-metal thermostatic element which has improved heat transfer characteristics and which may be adjusted without disturbing the means which provide the improved heat transfer characteristics.

These and other objects are effected by my invention as will be apparent from the following description and claims taken in connection with the accompanying drawing, forming a part of this application, in which:

Fig. 1 is a sectional view of my improved control mechanism taken on the line I—I of Fig. 2 and includes a diagrammatic view of a domestic refrigerator having my improved control mechanism applied thereto.

Fig. 2 is a sectional view of my improved control mechanism taken on line II—II of Fig. 1;

Fig. 3 is a detail view of one of the supports for the snap-acting thermal elements shown in Figs. 1 and 2.

Referring specifically to the drawing for a detailed description of my invention, numeral 11 designates a hermetically sealed casing containing a control mechanism generally designated at 12. The hermetically sealed casing 11 embodies a heat conducting cover member 13, preferably formed of a metal such as copper or brass and an

electrical and heat insulating base member 14, preferably formed of a material such as hard rubber or a molded plastic composition.

The base member 14 is provided with an opening 15 in which a tapped metal bushing 16 is disposed. A threaded shaft 17 is screwed into the metal bushing 16 and extends outwardly therefrom a considerable distance. A stop 20 in the form of a bolt head is provided at the end of the shaft 17 for a purpose hereinafter described. The supporting fingers 18, a detail of which is shown in Fig. 3, are molded into the base member 14. As shown in Fig. 2, three equally spaced supporting fingers 18 are provided adjacent the periphery of the base member 14. A bi-metal snap-acting disk 19 is supported by the fingers 18 and is provided with an aperture 21 in the center thereof through which the threaded shaft 17 extends.

An insulating bushing 22 is slidably mounted on the shaft 17 and a shoulder 23 thereof is held in engagement with the bi-metal disk 19 by a coiled spring 27. One end of the spring 27 engages a washer 30 on the bushing 22 and the other end engages a shoulder 28 in the base member 14. A movable contact member 25 is loosely mounted on the bushing 22 and is in engagement with one end of a coiled spring 24. A second shoulder 26 is provided on the bushing 22 and engages the movable contact member 25 when the switch mechanism is in the closed circuit position. Two stationary contacts 29, shown in Figs. 1 and 2, are mounted on the base member 14. Terminals 31 extend through the base member 14 and are connected to conductors 32. A rubber cap 33 may be clamped over the hermetically sealed casing 11 to protect the terminals 31 and provide an opening for the conductors 32.

I have shown my invention as applied to domestic refrigerating machines in which a motor 34 drives a compressor 35 to compress refrigerant and condense the same in a condenser 36 cooled by a fan 37. The condensed refrigerant is delivered through a conduit 38 to an evaporator 39, a portion of which is shown in Fig. 1, any suitable expansion device (not shown) being disposed between the condenser 36 and the evaporator 39. Vaporized refrigerant is returned to the compressor through a conduit 41. The conductors 32 connect a source of power L₁, L₂ to the switch terminals 31 and to terminals 42 on the motor 34. The bi-metal thermostatic element 19, therefore, opens and closes the circuit to the motor 34 in response to the temperature of the evaporator 39, the heat conducting cover

13 of the casing 11 providing for the passage of heat between the evaporator 39 and the bi-metal disk 19.

In accordance with my invention, each finger 18 is provided with a spring member 44 formed of a good heat conducting material, such as phosphor-bronze, and so positioned that it will contact with the metal heat conducting cover 13 when the cover 13 is in its assembled position on the base 14. The phosphor-bronze springs 44 provide increased heat transfer from the evaporator 39 to the interior of the sealed control mechanism 12 and to the bi-metal disk 19. By increasing the heat transfer from the evaporator 39 to the bi-metal disk 19 it is possible to use a bi-metal disk with a wide temperature differential because the amount of heat transferred to the bi-metal disk or abstracted from the bi-metal disk is much greater than in a case where the air or gas within the casing 11 is depended upon entirely for transferring heat to and from the bi-metal disk 19.

The temperatures of the evaporator 39 at which the bi-metal disk 19 respectively opens and closes the contacts 25, 29 may be varied substantially independently of each other. If it is desired to change the temperature of the evaporator 39 at which the bi-metal disk 19 closes the contacts, the shaft 17 is screwed into or out of the tapped metal bushing 16 so that the stop 20 is moved either towards or away from the disk 19. When the disk 19 snaps to the open contact position (not shown) the center of the disk engages the stop 20. Therefore, if it is desired to raise the temperature of the evaporator 39 at which the disk 19 will snap to close the contacts 25, 29 the stop 20 is positioned closer to the disk 19 so that when the disk is in the open contact position its internal stress will be increased, mechanically and less of a temperature change will be required to snap the disk. On the other hand, if it is desired to lower the temperature at which the evaporator 39 will snap the disk 19 to the closed contact position, the stop 20 is positioned further away from the disk 19 so that the stress in the disk 19 due to mechanical force, when in the open contact position, is lessened and a greater temperature change will be required to snap the disk to the closed contact position.

When it is desired to vary the temperature at which the contacts 25, 29 are opened, the position of the bi-metal disk 19 relative to the bushing 22 is changed by moving the disk 19 bodily in notches 45 provided in the fingers 18. For example, if it is desired to decrease the temperature at which the disk 19 opens the contacts 25, 29 from that shown in Fig. 1, the disk 19 is bodily moved to notches nearer the bushing 22 in fingers 18. The internal stresses in the bi-metal disk 19 are, therefore, increased mechanically and thus a reduction in the temperature of the disk 19 and the evaporator 39 is required to open the contacts 25, 29. On the other hand, if the bi-metal disk 19 is moved to notches 45 more remote from the bushing 22, the internal stresses in the bi-metal disk 19 are decreased and the temperature necessary to open the contacts 25, 29 will be lower. Since the bushing 22 is always in contact with the center of the disk 19, as the disk 19 is moved in the notches 45, the shoulder 23 of bushing 22 remains stationary so that only the edges of the disk 19 are moved, with the result that the disk assumes either a flatter position or a more concave po-

sition. It may then be necessary to change the position of the stop 20 to compensate for the change in position of the disk 19 in the notches 45, if it is desired to maintain the contact closing temperature the same. When the disk 19 is adjusted in the manner aforesaid, then only the temperature at which the evaporator 39 effects opening of the contacts 25, 29 is changed.

It will be apparent that the adjustments of the control may be made before the control is sealed and that the contact between the casing 11 and the phosphor-bronze springs 44 does not affect the manual adjustments of the control after the cover member 13 and the base member 14 are assembled.

If desired, the hermetically sealed casing 11 may be evacuated through a conduit 46 after which the casing 11 is preferably filled with inert gas such as nitrogen and the conduit 46 pinched off, so that oxidation of contacts 25, 29 is prevented.

In order to effect a complete hermetic seal, the base member 14 is provided with an annular notch 47 in which a gasket 48 of a resilient material such as rubber is disposed. The metal cover 13 is then disposed in its position on the base 14 and the edge thereof is rolled inwardly and downwardly, as shown at 49, by any suitable tool. This provides a very inexpensive method of hermetically sealing the casing 11 and also facilitates opening the casing for repairs, after which the cover 13 may be re-rolled to again provide a hermetic seal.

The control mechanism described, except for the addition of the phosphor-bronze springs 44, is completely disclosed and claimed in the co-pending application of Roger W. Hastings, Serial No. 260,517, filed March 8, 1939 for improvement in Control apparatus.

From the foregoing it will be apparent that I have provided an improved control mechanism of the bi-metal thermostatic type wherein a wide differential bi-metallic element may be utilized and wherein metal to metal contact between the thermostat and the casing is effected and the control mechanism may be adjusted prior to assembly of the enclosing casing.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. A switch structure embodying electrical contacts, a snap-acting bi-metal thermostat for opening and closing said contacts in response to changes in temperature, a plurality of supporting members for retaining said bi-metal thermostat in snap-acting position, a casing structure formed of separable members for enclosing said bi-metal thermostat, supporting members and contacts, said casing structure embodying at least a portion formed of a material of relatively high heat conductivity, and heat conducting means extending between at least some of said supporting members and the casing portion of relatively high heat conductivity, said casing portion of relatively high heat conductivity freely engaging said heat conducting means.

2. A switch structure embodying a casing comprising separable members, electrical con-

tacts disposed within the casing, a bi-metal thermostat also disposed within the casing for opening and closing said contacts in response to changes in temperature of an object or media exterior of the casing, means for adjusting the bi-metal thermostat so that it responds to different temperatures, and means for conducting

heat in a direct metallic path between the object or media exterior of the casing and the bi-metal thermostat, said last means being so arranged that when said casing is separated the adjustment of the bi-metal thermostat remains unchanged.

GERALD P. MARCY.
